(57) **CLAIM**

The ornamental design for a light for vehicles, as shown and described.

DESCRIPTION

1. Light for vehicles
2. Light for vehicles
- 1.1 : Front
- 1.2 : Back
- 1.3 : Left
- 1.4 : Right
- 1.5 : Top
- 1.6 : Bottom
- 1.7 : Perspective
- 1.8 : Perspective
- 1.9 : Enlarged
- 1.10 : Enlarged
- 2.1 : Front
- 2.2 : Back
- 2.3 : Left
- 2.4 : Right
- 2.5 : Top
- 2.6 : Bottom
- 2.7 : Perspective
- 2.8 : Perspective
- 2.9 : Enlarged
- 2.10 : Enlarged

Title: Light for vehicles; Use of the designs: automobile lighting; The shading lines in the reproductions 2.1 through 2.10 are used to show the surface of the claimed design, do not form part of the claimed design; The Fig. 1.9 is an enlarged view of Fig. 1.3; The Fig. 1.10 is an enlarged view of Fig. 1.4; The Fig. 2.8 is another perspective view of a light for vehicles showing the design 2; The Fig. 2.9 is an enlarged view of part of the Fig. 2.8; The Fig. 2.10 is a left view of the design 2 without the base.

1 Claim, 20 Drawing Sheets
